UNITED STATES PATENT OFFICE.

ALBERT J. FARMER, OF NEWARK, NEW JERSEY.

DESIGN FOR A PISTON FOR COMBUSTION-ENGINES.

56,347.

Specification for Design.

Patented Oct. 5, 1920.

Application filed February 7, 1920. Serial No. 357,107. Term of patent 14 years.

To all whom it may concern:

Be it known that I, ALBERT J. FARMER, a citizen of the United States, residing in the city of Newark, in the county of Essex and State of New Jersey, have invented a new, original, and ornamental Design for Piston for Combustion-Engines, of which the following is a specification, reference being had to the accompanying drawings, forming a part thereof.

In the drawings, the figure is a side elevation of a complete piston, showing my new design.

I claim:

The ornamental design for a piston for combustion engines, as shown.

ALBERT J. FARMER.
